UNITED STATES PATENT OFFICE

172,518

SCREW DRIVER HANDLE

Jacob Sackstein, Portsmouth, Va.

Application July 23, 1953, Serial No. 26,111

Term of patent 7 years

(Cl. D93—4)

To all whom it may concern:

Be it known that I, Jacob Sackstein, have invented a new, original, and ornamental Design for a Screw Driver Handle, of which the following is a specification, reference being had to the accompanying drawing, forming a part hereof.

Figure 1 is a side elevation of the screw driver handle, showing my new design;

Figure 2 is a top plan view of the screw driver handle.

I claim:

The ornamental design for a screw driver handle, as shown.
